UNITED STATES PATENT OFFICE.

ANDRÉ CASTELIN, OF PARIS, FRANCE, ASSIGNOR TO SOCIÉTÉ ANONYME D'ÉTUDES ET D'EXPLOITATION DES BREVETS A. CASTELIN POUR MACHINES AGRICOLES AUTOMOBILES, OF PARIS, FRANCE.

GRAIN-ELEVATING DEVICE FOR HARVESTING-MACHINES.

SPECIFICATION forming part of Letters Patent No. 763,854, dated June 28, 1904.

Original application filed January 9, 1902, Serial No. 89,085. Divided and this application filed December 22, 1902. Serial No. 136,239. (No model.)

To all whom it may concern:

Be it known that I, ANDRÉ CASTELIN, engineer, a citizen of the French Republic, residing at Paris, France, (and having post office address 17 Rue St. Florentin, in said city,) have invented certain new and useful Improvements in Grain-Elevating Devices for Harvesting-Machines, of which the following is a specification.

- 10 This invention relates to certain new and useful improvements in grain-elevating devices for harvesting-machines, and is a division of the application Serial No. 89,085, filed January 9, 1902.
- 15 The invention aims to construct a grain-elevating device for harvesters which is adapted to receive the grain when operating at a very low initial velocity, elevating the grain when the device is operating at an increasing speed, and depositing the grain upon a binder-table when the device has almost no speed.

20 The invention further aims to construct a grain - elevating device for harvesting - machines which shall be extremely simple in its construction, strong, durable, efficient in its use, and comparatively inexpensive to set up.

25 With the foregoing and other objects in view the invention consists of the novel combination and arrangement of parts hereinafter 30 more specifically described, illustrated in the accompanying drawings, and particularly pointed out in the claim hereunto appended.

In describing the invention in detail reference is had to the accompanying drawings, 35 forming a part of this specification, wherein like reference characters denote corresponding parts throughout the several views, and in which—

Figure 1 is a side elevation, partly in section, of the elevating device. Fig. 2 is a front view thereof, and Fig. 3 is a portion of the elevating device in perspective.

Referring to the drawings by reference characters, 1 denotes the endless apron of a 40 harvesting-machine and which is adapted to convey the grain to the elevating device, to be hereinafter referred to, so that the said elevat-

ing device can transport the grain from the endless apron 1 upon the table 2, where the sheaf is formed. Between the table 2 and the apron 50 1 is arranged a channel through which the grain ascends through the medium of the elevating device, and the channel is formed by two sheets of suitable material, preferably metal, one of which is designated by the reference character 3 and depends from the table 2 and the other of which is designated by the reference character 4 and is suitably secured a sufficient distance away from the sheet 3 to a fixed part of the harvesting-machine. 55

The grain-elevating device consists of a series of truncated shafts 5, extending in the same axial direction and mounted in bearings 6, which extend from one end of the machine to the other. The shafts 5 are provided with 60 the crank-arms 7 and 8, which form an angle of one hundred and eighty degrees with respect to each other. The crank-arms 7 are connected together in pairs by means of the shafts 9, and the crank-arms 8 are connected 65 together in pairs by means of the shafts 10. Articulated on the shafts 9 and 10 are the elevating-arms 11 and 12, respectively. The rear ends of the arms 11 are articulated to the links 14, and the rear ends of the arms 12 are articulated to the links 13. The links 13 14 are mounted upon the axles 15, which turn in the bearings 16.

When the outer shaft 5 is set in continuous motion through the medium of the shaft 17', 80 operating by the gear-wheels 19' and 19'', the shaft 17' being operated by the gear-wheels 78 and 19, to which motion is imparted by the main shaft 17 of the machine, it is obvious that the whole articulated system will then be 85 set in motion and that the ends of the elevating-arms will describe a trajectory, as shown by the curved dotted line 20, Fig. 1.

It will be evident that owing to the arrangement of the crank-arms 7 and 8 the 90 group of elevating-arms 12 will receive motion differing in one hundred and eighty degrees with respect to the motion of the group of elevating-arms 11. When the device is

operated, the elevating-arms at the lower part of the trajectory or curve which they describe are momentarily nearly stationary. Then as they ascend their speed increases first, remains 5 then nearly the same until they arrive at the upper part of the trajectory, where their speed decreases. The direction of travel of the arms is then changed, so that they will descend to the bottom of the trajectory or curve and then 10 move forwardly and upwardly to receive the grain. Owing to the foregoing operation, the grain is sized by the elevating-arms at the rear of the endless band or apron 1 (the latter is operated by the chain and chain-wheel 21 and 15 22) and is elevated through the channel between the plates 3 and 4 onto the table 2, where the grain accumulates and from which the sheaf is formed. It may be stated that the speed of the elevating-arms 11 and 12 at the 20 base of the curve or trajectory 20 is very slow and then gradually increases, so that the grain is gently taken hold of and raised with an in-

crease in speed, thus avoiding injury to the same.

Having thus fully described my invention, 25 what I claim as new, and desire to secure by Letters Patent, is—

A grain-elevating device for harvesting-machines, comprising a plurality of truncated shafts, crank-arms carried on each end of said shafts, shafts for connecting said crank-arms together in pairs, elevating-arms mounted upon the connecting-shafts, bearing-brackets for supporting said truncated shafts, axles supported by said brackets, and links for connecting said arms with the axles. 30 35

In testimony whereof I have hereunto set my hand in presence of two subscribing witnesses.

ANDRÉ CASTELIN.
